COMBINED CHALK LINE MARKER AND PLUMB
LINE OR SIMILAR ARTICLE

Robert W. Heuer, North Brunswick, N.J., assignor to Evans-Aristocrat Industries, Inc., Elizabeth, N.J., a corporation of New Jersey

Filed Feb. 8, 1966, Ser. No. 964

Term of patent 14 years

(Cl. D52—1)

FIG. 1 is a view of one side of the combined chalk line marker and plumb line showing my new design;

FIG. 2 is a side view;

FIG. 3 is a view of the other side thereof;

FIG. 4 is a top plan view thereof; and

FIG. 5 is a bottom plan view thereof.

Both sides have the appearance shown by FIG. 2.

I claim:

The ornamental design for a combined chalk line marker and plumb line or similar article, substantially as shown and described.
